(21) **Appl. No.:** **29/679,025**

The ornamental design for a third brake LED light base, as shown and described.

(22) **Filed:** **Jan. 31, 2019**

DESCRIPTION

(51) **LOC (12) Cl.** **26-06**

FIG. 1 is a perspective view of a third brake LED light base showing my new design;

(52) **U.S. Cl.**

FIG. 2 is another perspective view thereof;

USPC **D26/31**

FIG. 3 is a front elevation view thereof;

(58) **Field of Classification Search**

FIG. 4 is a back elevation view thereof;

USPC D26/28-36, 139

FIG. 5 is a left side view thereof;

CPC F21S 48/00; F21S 48/10; F21S 48/115;

FIG. 6 is a right side view thereof;

F21S 48/225; F21S 48/1233; F21S

FIG. 7 is a bottom plan view thereof;

48/1266; F21S 48/1388; F21S 48/2268;

FIG. 8 is a using state diagram when an LED light bar is fitted; and,

F21V 21/04; F21V 29/004; B60Q 9/13;

FIG. 9 is a using state diagram when a cover is closed.

B60Q 9/135; B60Q 9/1375

A top plan view is omitted, which is a mirror image of the bottom plan view.

See application file for complete search history.

The broken lines in the drawing depict environmental subject matter only and form no part of the claimed design.
